DESIGN FOR AN APPLIQUÉ EMBLEM OR SIMILAR ARTICLE

Leo A. Seltzer, Portland, Oreg.

Application June 1, 1937, Serial No. 69,650

Term of patent 14 years

To all whom it may concern:

Be it known that I, Leo A. Seltzer, a citizen of the United States and a resident of the city of Portland, Multnomah County, and State of Oregon, have invented a new, original, and ornamental Design for an Appliquéd Emblem or Similar Article, of which the following is a specification, reference being made to the accompanying drawing which forms a part thereof.

The view is a front elevation of an appliquéd emblem or similar article embodying my design.

The emblem possesses no substantial thickness.

I claim:

The ornamental design for an appliquéd emblem or similar article, substantially as shown and described.

LEO A. SELTZER.
